UNITED STATES PATENT OFFICE

170,557

COMBINED BLOTTER AND STAMP BOX

Harold A. Swan, Coronado, Calif.

Application January 7, 1953, Serial No. 23,046

Term of patent 14 years

(Cl. D74—1)

To all whom it may concern:

Be it known that I, Harold A. Swan, a citizen of the United States, residing at Coronado, State of California, have invented a new, original, and ornamental Design for a Combined Blotter and Stamp Box, of which the following is a specification, reference being had to the accompanying drawing, forming a part hereof.

Fig. 1 is an isometric view of a combined blotter and stamp box showing my new design;

Fig. 2 is a vertical cross-sectional view thereof; and

Figure 3 is a top plan view.

The side not shown follows the lines of the side disclosed.

I claim:

The ornamental design for a combined blotter and stamp box, as shown and described.

HAROLD A. SWAN.
